[57] CLAIM

The ornamental design for a fishing reel, as shown.

DESCRIPTION

FIG. 1 is a front, top and left side perspective view of a fishing reel showing our new design, with the reel in open bail position;

FIG. 2 is a right side elevational view thereof, with the reel in closed bail position;

FIG. 3 is a left side elevational view thereof;

FIG. 4 is a top plan view thereof;

FIG. 5 is a bottom plan view thereof;

FIG. 6 is a front elevational view thereof;

FIG. 7 is a rear elevational view thereof; and

FIG. 8 is a left side elevational view thereof, with the reel in open bail position.
